UNITED STATES PATENT OFFICE.

EDWARD E. CIHA, OF CHICAGO, ILLINOIS.

TOOL.

Application filed February 27, 1922. Serial No. 539,680.

To all whom it may concern:

Be it known that I, EDWARD E. CIHA, a citizen of the United States, residing at Chicago, in the county of Cook and State of Illinois, have invented certain new and useful Improvements in a Tool, of which the following is a description.

My invention relates to improvements in tools, and more particularly to an improved wrench for removing the caps of Mason jars and the like, and which may also be used for various other purposes, as for removing corks and crown caps, from bottles, opening cans, cracking nuts, etc. One of the objects 10 of my invention is to provide a tool as above described, having means for adjusting the object-gripping portions thereof so that various sizes of objects may be handled thereby. The invention has among its other 20 objects the production of a device of the kind described which is simple, convenient, compact, economical, durable, reliable and satisfactory for use wherever found applicable. Many other objects and advantages of the 25 construction herein shown and described will be obvious to those skilled in the art from the disclosure herein given.

To this end my invention consists in the novel construction, arrangement and combination of parts herein shown and described, and more particularly pointed out in the claim.

In the drawings, wherein like reference characters indicate like or corresponding 35 parts,

Fig. 1 is a plan view of the device;

Fig. 2 is a sectional view taken substantially on the line 2—2 of Fig. 1;

Fig. 3 is a section taken substantially on 40 the line 3—3 of Fig. 1; and

Fig. 4 is a section taken substantially on the line 4—4 of Fig. 1.

In the drawings, wherein I have illustrated the preferred embodiment of my invention, there is shown a wrench comprising a pair of members 1 and 2 pivotally and adjustably connected together. Each of said members as illustrated has a handle portion 3, a jaw or head portion 4 and a laterally offset portion 5 and 6, on the members 1 and 2 respectively, beyond said head portions. The head portions are formed with arcuate recesses 7, so that when the parts 1 and 2 are pivotally assembled as shown, the registering recesses 7—7 will form an object-receiving opening therebetween. In order to more

firmly grip the object between the jaws or heads 4 of the tool, the bounding gripping edges of the recesses have serrations or teeth 8 formed therealong, as shown more clearly 60 in Fig. 1. It will be noted that these teeth are not sharp, but flat so that they will firmly grip the cover without denting or marring it. One or more preferably smaller auxiliary object-receiving openings may be 65 formed between the recesses 7—7 and the offset extensions 5 and 6 by forming pairs of cooperating recesses 9—9 with teeth thereon similar to the main recesses 7—7.

One of offset extensions, as for instance 70 the part 5, has an elongated slot or opening 10 therethrough, and opening into said slot are a series of spaced offset notches 11. A pin 12 is secured to the other extending part 6, said pin being slidable in the slot 10 so 75 that it may be moved into either of the notches 11. The pivotal connection may be located as desired and be of any preferable construction. Thus there is provided an adjustably pivotal connection at one end where- 80 by the object-receiving openings may be enlarged or decreased in size to accommodate the various sizes of objects to be gripped between the gripping edges of the jaws.

The purpose of the auxiliary opening 9, 9 85 is to remove small caps or covers from bottles or jars, or any other type of container and to remove corks or the like therefrom, and they may also be used for the purpose of cracking the shells of nuts, if so desired. 90

A bottle-opening prong or hook 13 may be formed at one end of the recess 7 in one of the members, as shown, in the member 2, whereby crown caps or the like may be removed. A can opener knife blade 15 may 95 be secured to the inner edge of one of the handles, if so desired, said blade being secured to said handle in any well known manner, as by welding, or by a rivet 16 as shown. The can opener does not interfere with the other uses of the device, as it is on the inner side of the handles. A knife sharpener 17 and a cork screw 18 may also be secured on the handle portion of the device, preferably 100 on the inner side thereof, as shown.

In order to reinforce or stiffen the operating handles and the heads of the tool, there is provided a flange 14 bounding the edges of said parts. This also makes the device more comfortable in the hand. Thus there is provided a tool which is extremely strong and 110 sturdy in construction, easy to operate, and

which may be adjusted to accommodate various sizes of Mason jars, caps, corks or the like, and which may also be used for the purpose of cracking nuts and removing crown caps from bottles or opening tin or like cans. While the parts are pivotally and adjustably connected together, it will be noted that in the preferred embodiment of the invention shown, the parts are always retained assembled, so that they form a unitary structure, and parts cannot be mislaid or lost.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

In a tool of the kind described and in combination, a pair of sheet metal members each comprising a handle, a jaw portion, and a portion beyond said jaw extending laterally thereof, each of said jaw portions having a main and an auxiliary arcuate recess formed therein, those of one jaw registering

with those of the other so that when assembled there will be formed a plurality of pairs of spaced object-receiving gripping openings between the registering recesses of both members, said recesses having serrated edges, one of said laterally extending portions beyond the jaw having an elongated slot longitudinally thereof with a series of notches offset therefrom and communicating therewith, the other of said longitudinally extending portions having a pin slidably engageable in said slot and movable into either of said notches, whereby said object-receiving recesses may be adjustably varied in size, said members provided with a flange along the bounding edges of said handle portions to form a channel and provided with a flange along the outer edge of the jaw portion so that said portion will be reinforced and suitable tools may be carried by said handles.

In testimony whereof, I have hereunto signed my name in the presence of two subscribing witnesses.

EDWARD E. CIHA.
